Primary Examiner — Wan Laymon(74) *Attorney, Agent, or Firm* — Frank J. Bonini, Jr.; John F. A. Earley, III; Harding, Earley, Follmer & Frailey, P.C.(57) **CLAIM**

The ornamental design for an orthodontic tensioning device, as shown and described.

DESCRIPTION

FIG. 1 is a perspective view of an orthodontic tensioning device in accordance with our new design, illustrated with the connectors shown in broken-line;

FIG. 2 is a top plan view of FIG. 1, the bottom plan view being a mirror image thereof; and,

FIG. 3 is a right side elevation view of FIG. 1, the left side view being a mirror image thereof.

The broken lines in FIGS. 1, 2, and 3 are for illustrative purposes and form no part of the claimed invention.
